UNITED STATES PATENT OFFICE.

HERMANN NIKOLAUS, OF VIENNA, AUSTRIA-HUNGARY.

SLIDING WINDOW.

1,078,369.

Specification of Letters Patent.

Patented Nov. 11, 1913.

Application filed March 28, 1911. Serial No. 617,438.

To all whom it may concern:

Be it known that I, HERMANN NIKOLAUS, subject of the Emperor of Austria-Hungary, residing at Ungargasse 59, Vienna, 5 III, Austria-Hungary, have invented certain new and useful Improvements in Sliding Windows, of which the following is a specification.

This invention relates to a sliding window of which the sashes are all slideable, and also capable of tilting inwardly, and balanced by means of counter-weights hung on wire cords working behind the window frame.

15 In the tilting movement of the sashes the bearing of the pivot of the sash is completely locked so that the tilted sash cannot shoot upward owing to the action of the counterweights.

20 The means for guiding the sashes consist of a fixed lower guide pin and a retractile upper guide pin; these guide pins being slideable in guide grooves as is well known in the art. The outer guide groove 25 is vertical. The inner guide groove is vertical in its upper part and inclines at the lower end and joins the outer guide groove at an acute angle at the window sill.

An antifriction roller for the wire cord is 30 located at the apex of the obtuse angle, and the apex of the acute angle is protected by an iron shoe. By this means the sliding of the sashes causes only very little friction because the wire cord comes in contact only 35 with the antifriction roller which by its easy working practically annuls the friction. This arrangement also enables sashes of very great width to be moved very easily.

My invention will be more clearly understood by reference to the accompanying drawing, in which:

Figure 1 is a vertical section of the window showing the sashes closed. Fig. 2 is a fragmentary sectional plan with the sashes 45 closed. Fig. 3 is a detailed view of the locking means for the pivot bearings. Fig. 4 is a similar view taken at right angles to the Fig. 3. Fig. 5 is a view similar to Fig. 3 showing in dotted lines the locking means 50 in locking position.

The lower guide pins 8 to which the wire cords are attached, are secured in position to the sashes, and they serve also as pivots for the tilting movement of the sashes.

55 The top sashes O operate in exactly the same manner as the bottom sashes.

The acute angle formed by the junction of the two guide grooves is protected on all sides by a metal shoe 6 (Figs. 1 and 3).

An antifriction roller 4 with bearing plates 5 (Fig. 1) is provided for the wire rope at the apex of the angle of the inner guide groove for the purpose of preventing all contact between the wire cord and the sides of the guide groove, and consequent 60 damage to the cord, so that there is only one place of friction in the rising movement of the sash, and therefore even very heavy sashes can be raised with extreme ease.

The two pairs of sashes U¹, U², and O¹, 70 O² engage with each other by means of interfitting surfaces in such a manner as shown in Fig. 1, as to form between the inner and outer sashes an air space which is entirely isolated from the outside, and 75 the sashes fit quite tight to the window frame by means of a four-fold joint, so that the improved window sashes close tighter than ordinary existing window sashes.

The sashes are connected to the lower 80 cross pieces by hinges and to the upper cross pieces by a friction fastening so that they can be separated from each other for the purpose of cleaning the window glass on the inside.

The pivot bearing 21 shown in Figs. 3 and 5, has inserted in it a round disk 23 which is open at the top and has a slot. The pivot bearing plate has a circular recess 22 which is smaller than the disk 23 said 90 recess connecting with the groove 23^a as shown in Fig. 3.

24 is a projection provided on the upper edge of the pivot bearing plate.

The lower guide pin 8 which serves as a 95 pivot is not round, but is polygonal and fits exactly in the recess in the disk 23. In the tilting movement of the sash, the guide pin consequently takes the disk 23 along with it and thus completely closes the open-topped 100 recess in the pivot bearing plate. The angle piece 25 is circular at the top and slides under the projection 24 so long as the recess in the pivot bearing plate is left open.

Having now described my invention what 105 I claim as new and desire to secure by Letters Patent is:

1. In a sliding window, the combination with a sliding counterweighted sash, of an inner grooved guide for the lower sash composed of two rectilinear portions forming an obtuse angle, an outer grooved guide joining 110

- said inner grooved guide, a lower guide pin on the sash, an open topped pivot bearing for said guide pin located at the junction of the inner and outer guides, and a rotatable pivot bearing plate having a recess in which the lower guide pin enters when the sash is lowered, said bearing plate being adapted to lock the sash temporarily in position.
2. In a sliding window, a grooved guide, a window sash having a guide pin working in the grooved guide, means for permitting the sash to tilt, and rotatable means disposed at the bottom of the grooved guide to lock the sash against upward movement when the latter is tilted said rotatable means being concentric with the guide pin.
3. In a sliding window, a grooved guide, a sash having a guide pin working in the grooved guide, and a rotatable slotted disk disposed in the grooved guide for engagement with the guide pin to lock the sash against upward movement.
4. In a sliding window, a window casing provided with vertically grooved guides, a window sash in the casing having guide pins traversing the grooved guides, locking plates located adjacent to the bottom of the grooved guides and provided with slots extending inwardly from the periphery of said plates toward their centers, said slots being normally in communication with the grooved guides to receive the guide pins of the sash when the latter is lowered, and means for actuating the locking plates when the sash is tilted to move the slots in the plates out of communication with the grooved guides for locking the sashes against upward movement.
5. In a sliding window, an outer grooved guide, an inner grooved guide parallel with the outer grooved guide for a portion of its length and connected to the outer guide at the bottom thereof by a branch guide, a lower sash having a guide pin working in the inner and branch grooved guides, means permitting the sash to swing inwardly on the guide pin as a pivot, and a rotatable disk disposed at the bottom of the outer grooved guide and provided with a slot to receive the guide pin of the sash when the latter is in its lower position.
6. In a sliding window, an outer grooved guide, an inner grooved guide parallel with the outer grooved guide for a portion of its length and connected to the outer guide at the bottom thereof by a branch guide, a lower sash having a guide pin working in the inner and branch grooved guides, means permitting the sash to swing inwardly on the guide pin as a pivot, a slotted disk disposed at the bottom of the outer grooved guide with the slot in alignment with said outer grooved guide, and a square portion on the guide pin for rotating the disk when the sash is tilted.
7. In a sliding window, a grooved guide, a disk located at the bottom of the grooved guide and provided with a slot in alignment therewith, a sash having a guide pin working in the grooved guide, means to permit the sash to tilt inwardly, and means on the guide pin to rotate the disk to lock the sash against upward movement when the latter is tilted.
- In testimony whereof I affix my signature in presence of two witnesses.
- HERMANN NIKOLAUS.
- Witnesses:
- JOSEF FABRY,
AUGUST FUGGER.
